UNITED STATES PATENT OFFICE.

FRANK BALINT, OF BRIDGEPORT, CONNECTICUT.

ELECTRIC SWITCH.

Application filed March 17, 1924. Serial No. 699,740.

To all whom it may concern:

Be it known that FRANK BALINT, a subject of Hungary, and resident of Bridgeport, in the county of Fairfield and State of Connecticut, has invented certain new and useful Improvements in Electric Switches, of which the following is a specification.

This invention relates to an improved switch for use particularly with automobile stop and direction signalling devices, and has for an object to provide a switch of this character which will be simple and reliable in construction and operation, and by means of which a series of signalling elements may be operated in succession.

A further object is to provide a switch in which a switch lever will make contact in one direction of movement, and will move out of contact in the other direction, so that no reversal of signals will occur, and further to provide improved means for making and breaking the battery circuit, when desired.

With the above and other objects in view, an embodiment of the invention is shown in the accompanying drawings, and this embodiment will be hereinafter more fully described with reference thereto, and the invention will be finally pointed out in the claims.

In the drawings:

Fig. 1 is a front elevation of a switch device, according to the present embodiment of the invention;

Fig. 2 is a side elevation of the same;

Fig. 3 is a vertical sectional view, taken along the line 3—3 of Fig. 2;

Fig. 4 is a vertical sectional view, taken along the line 4—4 of Fig. 1;

Fig. 5 is a side elevation, and showing the handle portion of the switch lever in inoperative position;

Fig. 6 is a front elevation of a modified switch adapted to be connected to the foot brake to be operated thereby; and

Fig. 7 is a diagrammatic view showing the two switches and the signalling elements, and the wiring arrangement.

Similar reference characters indicate corresponding parts throughout the several figures of the drawings.

Referring to the drawings, the embodiment of the invention shown therein comprises a casing 10 of substantially semi-circular form adapted to be secured to a

dash by lugs 11 and 12, and provided in its periphery with a slot 13 in which the switch lever is adapted to move. The casing is provided at one side with a series of spaced contacts 14, 15, 16, 17, 18, 19 and 20 arranged in an arc and insulated from said side of the casing by insulating plates 21 and 22 secured at each side thereof by the threaded shanks of the contacts and terminal wire retaining nuts 23 screwed thereon. An arcuate battery contact 24 is also provided in inwardly spaced relation to said series of spaced contacts, and is secured by a nut 25 engaged upon its threaded shank. 70

The switch lever is loosely pivoted upon a transverse shaft 26 mounted in the casing, and comprises an insulating block 27 carrying a contact piece 28 at one side adapted to span and contact with the spaced contacts and the contact 24, and a metal back 29 secured at the other side and having a portion 30 extended through the slot 13. A spacer collar 31 is disposed between the lever and insulating plate 21 and the lever is yieldably pressed into engagement with the contacts by a spring 32 coiled about the shaft 26, while a bowed leaf spring 33, mounted upon the shaft and held against the lever by the spring 32, presses against the upper portion of the lever between retaining lugs 34 to yieldably maintain the lever in right-angular position with respect to the shaft. 75

At the upper end of the lever there is 90 hingedly mounted a handle 35 yieldably held in its upright operative position (Fig. 2), or in its forwardly moved inoperative position (Fig. 5), by a flat spring 36 secured to the lever and engaging the flat rear side of the handle in said upright position, and the flat lower end in said forwardly moved inoperative position. 95

In said forwardly moved position the handle engages in the opening of a bifurcated plate 37 secured upon the casing 10 to hold the lever against swinging movement in either direction, and at the same time camming lugs 38 disposed at each side of the handle above the pivot engage the inner face of the plate 37 and force the lever rearwardly, as shown in Fig. 5, thereby disengaging the switch lever contacts 28 from the battery and spaced contacts and rendering the switch inoperative, the circuit to the battery being broken. 100

The contact 14 is connected to a brake

operated stop signal switch, hereinafter more fully referred to, so that in the upright position of the switch lever (Figs. 1 and 2) the circuit from the battery to the 5 brake switch is closed by engagement of the contact 28 with the contacts 24 and 14, while in the inoperative position, (Fig. 5) this circuit is broken and the brake switch rendered inoperative. In the signal operating 10 position of the switch lever, as indicated in dotted lines in Fig. 3, the circuit to the brake switch is opened, so that this switch will be inoperative during operation of the other signal means.

15 Upon the inner peripheral surface of the casing, and at each side of the central position of the switch lever, arcuately disposed inclined leaf springs 39 are secured at their upper ends by means of brackets 20 40, and upon the portion 30 of the switch lever there is provided a lug 41 having a right angularly bent end adapted as the switch lever is swung downwardly at either 25 side to engage upon the surface of the spring 39 adjacent the contacts, the spring being sprung rearwardly by this engagement until released in the extreme moved position of the lever, as indicated in dotted lines in Fig. 3, the end of the spring then 30 being forwardly of the lug 41. Upon return movement of the switch lever the lug will therefore engage the rear side of the spring, thereby camming the switch lever out of engagement with the contacts to prevent a reverse operation of the signals.

35 In Fig. 6 there is illustrated a form of stop signal operating brake actuated switch, according to the invention, comprising a casing 42 of substantially semi-circular form, having a slot 43 in its periphery in which the switch lever 44, pivoted upon a shaft 45, is adapted to move, being normally held in its inoperative position by a spring 46 and adapted to be swung to operative 40 position, upon movement of the foot brake, by means of a wire 47 connected to the foot brake rod. A pair of spaced arcuately disposed contacts 48 and 49 are provided on one side of the casing, the contact 48 adapted 45 to connect with an audible signal, and the contact 49 to a visible signal, and in inwardly spaced relation thereto, there is provided an elongated battery contact 50, the switch lever carrying an elongated insulated 50 contact piece 51 adapted to span the battery contact and the contacts 48 and 49, to first close the circuit of the audible signal and then close the circuit of the visible signal. In order to disengage the switch from the contacts during return movement to thereby prevent reverse operation of the signals, a leaf spring camming member 52, similar to the camming springs 39, is provided upon the inner peripheral surface of the casing 55 and is engaged by a lug 53 on the lever to

engage the contacts in one direction of movement and to disengage them in the other direction of movement.

As shown diagrammatically in Fig. 7, the switches are adapted to be connected to an 70 audible signal, as a horn 54, a visible signal, as a lamp 55, and left and right signal devices 56 and 57, the lighting of the lamp adapted to indicate "Stop", and the lamp also adapted to be lighted during actuation 75 of the "Left" and "Right" signals to illuminate them.

The wiring arrangement is as follows:

A lead 58 from the battery is connected to the contact 24, and a lead 59 extends from the contact 14 of the dash switch to the contact 50 of the brake switch, so that the brake switch may be disconnected from the battery by swinging the handle 35 to the inoperative position, (Fig. 5) and also during movement of the same to either the right or left signal operating positions, so that only one signal will be operative at a time. The horn 54 is connected by leads 60 to the horn contacts 15, 18 and 48 of the dash and brake switches, and the lamp 55 by leads 61 to the light contacts 16, 19 and 49 of the two switches, while the left and right signal devices are connected by leads 62 and 63 to the left and right contacts 20 95 and 17 of the dash switch.

Upon operating the brake, the brake switch is actuated to first sound the horn and thereupon light the lamp 55. By moving the dash switch to the left or right the horn is first sounded, the lamp then lighted, and the left or right signal devices, as the case may be, are operated, the lamp continuing to be lighted during the operating of said signal devices, the contact piece 28 engaging both the light and signal contacts in the moved position, as indicated by dotted lines in Fig. 3.

I have illustrated and described a preferred and satisfactory embodiment of the invention, but it will be obvious that changes may be made therein, within the spirit and scope thereof, as defined in the appended claims.

Having thus described my invention, what I claim and desire to secure by Letters Patent is:

1. A switch of the character described, comprising a casing, a series of spaced contacts in said casing, a pivoted switch lever normally in engagement with one of said contacts and adapted to be moved into engagement with the others, locking means adapted to be actuated to prevent swinging movement of said lever, and means adapted to move said lever out of engagement with said contact, normally engaged thereby, in said locked position of the lever.

2. A switch of the character described, comprising a casing, a series of spaced con-

10 contacts in said casing, a pivoted switch lever normally in engagement with one of said contacts and adapted to be moved into engagement with the others, a pivoted extension on said lever, locking means on said casing, said extension adapted to be engaged therewith to lock the switch lever against swinging movement, and cam means adapted to move said lever out of engagement with said contact, normally engaged thereby, in said locked position of the lever.

15 3. A switch of the character described, comprising a casing, a series of spaced contacts in said casing, a transverse shaft mounted in said casing, a switch lever loosely and pivotally mounted on said shaft, spring means on said shaft adapted to normally maintain said lever in a right angular relation to said shaft and in yielding en-

gagement with said contacts, said switch 20 lever being normally in engagement with one of said contacts and adapted to be moved into engagement with the others, locking means adapted to be actuated to prevent swinging movement of said lever, 25 and means adapted to move said lever against the force of said spring means out of engagement with said contact, normally engaged thereby, in said locked position of the lever.

30 Signed at Bridgeport, in the county of Fairfield and State of Connecticut, this 14th day of March A. D., 1924.

FRANK BALINT.
